UNITED STATES PATENT OFFICE.

BEATRICE EVA LINDBERG, OF FARIBAULT, MINNESOTA.

KINDERGARTEN-LOOM.

SPECIFICATION forming part of Letters Patent No. 703,799, dated July 1, 1902.

Application filed April 4, 1902. Serial No. 101,386. (No model.)

To all whom it may concern:

Be it known that I, BEATRICE EVA LINDBERG, a citizen of the United States, and a resident of Faribault, in the county of Rice 5 and State of Minnesota, have invented new and useful Improvements in School-Looms, of which the following is a full, clear, and exact description.

The invention relates to educational appliances; and its object is to provide a new and improved hand school-loom for use by school children in industrial work and arranged to hold the warp properly stretched and spaced apart and to permit of conveniently beating 15 in the weft to insure perfect work.

The invention consists of novel features and parts and combinations of the same, as will be more fully described hereinafter and then pointed out in the claims.

20 A practical embodiment of the invention is represented in the accompanying drawings, forming a part of this specification, in which similar characters of reference indicate corresponding parts in both views.

25 Figure 1 is a plan view of the improvement, and Fig. 2 is a sectional side elevation of the same on the line 2 2 of Fig. 1.

The school-loom consists, essentially, of an open frame having parallel side bars A A 30 and the ends B B, projecting suitable distances above the top faces of the side bars A A and formed in the top with notches for the passage of the warp C to hold the strands thereof stretched from one end to the other 35 and properly spaced apart, as will be readily understood by reference to Fig. 1. The strands of the warp C also extend between the ends B B through slots D', formed in the upper portion of a lay D, mounted to slide on the side bars A A to hold the warp-strands 40 between the ends B B in proper position and to allow of beating in the weft E, interwoven transversely with the warp C in the usual manner—that is, by the child passing a needle 45 up and down between adjacent warp-strands.

The lay D is in the form of a bar formed with shoulders D², engaging the upper and

inner faces of the side bars A A, as plainly shown in Fig. 2, to hold the lay in proper position on the side bars and to allow of conveniently sliding the same along the side bars for beating-in purposes, as above explained. 50

The lay extends from the top faces of the side bars A A a distance somewhat higher than the ends B B to prevent the warp- 55 strands from accidentally passing out of the said slots when the child passes the weft through the warp-strands by the use of the needle, thus preventing accidental displacement of the warp-strands. 60

Having thus described my invention, I claim as new and desire to secure by Letters Patent—

1. A school-loom having a frame provided with means for supporting the warp, and a 65 lay manually slideable on the sides of the loom-frame and having spaced slots for the passage of the warp-strands, to hold the latter properly spaced apart, the said lay having shoulders for engaging the top and inner 70 sides of the side bars of the loom-frame, the lay extending farther above the top faces of the side bars of the loom-frame than the ends thereof, as set forth.

2. A loom, comprising a frame having parallel side bars, and end bars projecting above the top faces of the side bars, the end bars being formed in the top with notches for the passage of the warp, and a lay comprising a bar manually slideable on the sides of the 80 frame and extending farther above the top faces of the side bars than the ends of the frame, the lay having spaced slots in the top for the passage of the warp-threads to hold the latter properly spaced apart, the lay also 85 serving to beat in the weft, as set forth. 75

In testimony whereof I have signed my name to this specification in the presence of two subscribing witnesses.

BEATRICE EVA LINDBERG.
